(57) CLAIM

The ornamental design for a trouser leg bottom, as shown and described.

DESCRIPTION

FIG. 2 is a front elevation view;

FIG. 3 is a rear elevation view; and,

FIG. 4 is a bottom plan view.
